SAFETY SWITCH DEVICE
Filed Oct. 2, 1929

UNITED STATES PATENT OFFICE

NORMAN LEINAU, OF YONKERS, NEW YORK, ASSIGNOR, BY MESNE ASSIGNMENTS, TO NORLEIN RESEARCH LABORATORIES, OF HACKENSACK, NEW JERSEY, A CORPORATION OF NEW JERSEY

SAFETY SWITCH DEVICE

Application filed October 2, 1929. Serial No. 396,862.

My invention consists in new and useful improvements in a safety appliance for indicating danger in connection with boilers and the like and includes means for automatically 5 breaking an electric circuit to either shut off the current of the heater or actuate other suitable means of control.

The object of my invention is to provide a device of this character which will not only 10 warn the operator or occupant of the premises, of any impending danger due to low water in a boiler, but will automatically terminate the operation of the heating mechanism until said operator actually removes the 15 danger by replenishing the water supply and resets the safety device by hand.

Heretofore with devices of this general 20 type, a thermostat, diaphragm or other similar element has been employed to automatically break a circuit to shut off the source of heat, but when the water in the boiler fell below the temperature required to operate the device, said device automatically returned to a contacting position which in turn caused 25 the heating mechanism to again be set into operation, which in time, if not attended to, would burn out the boiler and result in considerable damage. It is to overcome the disadvantages and dangers of this type of 30 device that I have evolved the present invention.

A further object of my invention is to provide a safety device, the working parts of 35 which are outside of the boiler, thereby not only being safer but more readily accessible.

A still further object of my invention is to provide an adjustable structure which may be set for various temperatures, the working 40 parts of said device being inclosed within a housing equipped with a transparent cover, whereby the works are visible from the outside.

With the above and other objects in view 45 which will appear as the description proceeds, my invention consists in the novel features herein set forth, illustrated in the accompanying drawings and more particularly pointed out in the appended claims.

50 Referring to the drawings in which nu-

merals of like character designate similar parts throughout the several views.

Fig. 1 is a front view of the device.

Fig. 2 is a longitudinal sectional view.

Fig. 3 is a side elevation from the side opposite that shown in Fig. 2.

Fig. 4 is a view similar to Fig. 1 with the cover removed.

Fig. 5 is a view showing the contacts in open position.

In the drawings, 1 represents a conventional boiler provided in one wall with an inwardly projecting chamber 2 closed at its inner end to the interior of said boiler, and provided at its outer end or mouth with an internally threaded collar 3.

4 represents an elongated tube, closed at one end by a cap 4^a and threaded at its other end to engage an enlarged cylindrical member 5. This member 5 is externally threaded 70 at the end which engages the tube 4 whereby it is adapted to be screwed into the collar 3 to secure said tube within the chamber 2 of the boiler. The member 5 is squared as at 6 to facilitate the application of a wrench or 75 other suitable tool in securing the device in place.

7 designates a base member adapted to be secured to the outer end of the member 5 at its lower end by means of an L-coupling 5^a, 80 its upper extremity carrying the lower end of a Bourdon tube 8, said Bourdon tube being in communication with the tube 4 by means of a conduit extending through the base member 7 and the member 5. Any suitable 85 liquid may be employed within the tube 4 and Bourdon tube 8 but I prefer the use of alcohol.

Surrounding the Bourdon tube and supported by the base member 7 is a housing 9 90 for inclosing the working parts of the device. An insulating base 10 is secured to the rear wall of the housing 9, substantially centrally thereof and within the confines of the Bourdon tube, said base 10 carrying an adjustable 95 pivoted resilient contact arm 11, the free end of which is provided with a lug 12 of insulating material.

13 represents a stationary contact arm also carried by said base 10 and adapted to engage 100

the resilient contact arm 11 when the latter is forced outwardly, thus completing a circuit for operating the boiler heating mechanism (not shown). The arm 11 is retained in contact position with the arm 13 by means of the lug 12 on the end of the former which engages the end of the Bourdon tube, serving as a latch.

Intermediate the ends of the contact arm 11 I provide a series of apertures 14 whereby said arm when adjusted on its pivot is adapted to be secured in the proper position by means of a screw which extends through the desired aperture into the insulating base 10. 15 If desired the outer face of the arm 11 may be provided with a graduated scale adjacent the series of apertures.

15 represents a cover adapted to fit over the open end or mouth of the housing 9 and 20 provided with a transparent window 16, whereby the working parts of the device are visible from the outside.

17 represents a resetting device which extends inwardly through the rim of the cover 25 15 and is secured to the insulating lug 12 on the end of the contact arm 11, whereby the latter may be pulled outwardly and reset.

On the end of the lug 12 and projecting longitudinally outwardly therefrom I provide 30 an indicating arm 18 which extends through a transverse slot 19 in the annular wall of the housing 9, the outer surface of which wall is provided with suitable indicia to enable the operator to ascertain the position of the resilient contact 11.

Having thus described the construction of my improved device, its operation is as follows:

When the boiler heating mechanism is in 40 operation the elements of the safety device are in the positions shown in Fig. 4 with the arms 11 and 13 in contact, closing the circuit, said arm 11 being retained in its contacting position by the end of the Bourdon tube engaging the lug 12.

If the water in the boiler becomes low and its temperature reaches the danger point, predetermined by setting the contact arm 11, the alcohol or other fluid in the tube 4 expands 50 and causes the end of the Bourdon tube to be moved outwardly releasing the lug 12 and permitting the resilient arm 11 to spring inwardly breaking its contact with the arm 13. This of course, opens the electric circuit and automatically shuts off the heating mechanism.

Information that the heat has been turned off may be transmitted to the occupant of the 60 premises or operator of the apparatus in any suitable manner such as a bell operated when the switch is opened. But the important feature is that before the heating mechanism is turned on again it is necessary for the operator to reset the device by hand, before which,

of course, he corrects the water level in the boiler and removes any danger.

When it is desired to again set the heating mechanism into operation, the resetting device 17 is pulled outwardly by hand and with it the resilient arm 11 permitting the Bourdon tube to spring inwardly and again lock the contact arms in circuit making positions.

From the foregoing it is believed that the advantages of my invention may be readily understood by those skilled in the art, it being borne in mind that numerous changes may be made in the details of the construction without departing from the spirit of the invention.

It will also be noted that this device may be employed with various types of apparatus such as, oil heaters, fire alarms, hot water heaters, etc.

It will be further noted that while I have shown and described the resetting device 17, applied to the front of the structure and operated by pulling out, I may, with equal advantage, insert the same from the rear wall of the housing 9, passing it through the insulating block 10 where it will abut the rear face of the resilient arm 11, whereby the latter may be pushed into contact position rather than pulled. A suitable spring may be employed on the resetting device to return the same to its normal position.

What I claim and desire to secure by Letters Patent is:—

1. In a safety switch device for electrically controlled apparatus, an expandible member and a movable contact lying in the same plane but operatively movable in different planes, said expandible member being arranged to engage said contact to lock the same in circuit closing position, when retracted, and to disengage said contact when extended.

2. In a safety switch device for electrically controlled apparatus, a Bourdon tube and a movable contact, lying in the same plane but movable in planes at substantially right angles to one another, the end of said Bourdon tube being arranged to engage said contact to lock the same in circuit closing position when retracted, and to disengage said contact when extended.

3. In a safety switch device for electrically controlled apparatus, a stationary contact, a movable contact normally lying in substantially the same plane and adapted to engage said stationary contact to close an electrical circuit, and a heat actuated expandible member adapted to engage said movable contact when retracted, to maintain said contacts in circuit closing position, said member disengaging said movable contact when extended, the plane of movement of said second contact being at substantially right angles to that of said expandible member.

4. In a safety switch device for electrically controlled apparatus, a stationary contact, a movable contact adapted to engage said stationary contact to complete an electric circuit, the end of said movable contact being provided with an insulating member, an expandable member, the free end of which is adapted to engage the insulating member on said movable contact when retracted, to maintain said contacts in engagement, said expandable member disengaging said insulating member when extended, the movement of said second contact being in a plane at substantially right angles to that of said expandable member.

5. In a safety switch device for electrically controlled apparatus, a stationary contact, a movable contact adapted to engage said stationary contact to complete an electric circuit, the end of said movable contact being provided with an insulating member, a Bourdon tube, the free end of which is adapted to engage the insulating member on said movable contact when retracted, to maintain said contacts in engagement, said tube disengaging said insulating member when extended, the movement of said second contact being in a plane at substantially right angles to that of said Bourdon tube and manually controlled means mounted on said movable contact for resetting the same.

6. A safety switch device comprising a housing, a Bourdon tube and a resilient contact in said housing, the latter being secured at one end and provided with an insulating member at its free end, the free end of said Bourdon tube being arranged to engage the free end of said contact, when retracted, to lock the same in circuit closing position, and to disengage said contact when extended, and a resetting device secured to the free end of said resilient contact, projecting through said housing.

7. A safety switch device comprising a housing, an insulating block in said housing, a stationary contact secured to said block, a movable contact also secured to said block, a heat actuated expandable member rigidly secured at one end within said housing, its other end being free and adapted to engage said movable contact, when retracted, to lock the same in circuit closing position, and to disengage said contact when extended, said movable contact being adjustable in the plane of movement of said expandable member.

8. A device as claimed in claim 7 wherein in the wall of said housing is provided with a slot, said movable contact having an indicating arm secured thereto and extending through said slot to indicate the position of said contact.

9. A device as claimed in claim 7 wherein said stationary contact and said movable contact are adjustable in the plane of movement of said expandable member.

10. A device as claimed in claim 7, wherein the movement of said movable contact is in a plane at substantially right angles to that of said expandable member.

In testimony whereof I affix my signature. ⁷⁰
